UNITED STATES PATENT OFFICE

166,949

GAME APPARATUS FOR THE SPELLING OF WORDS

William S. Brodes, New Haven, Conn.

Application May 17, 1950, Serial No. 9,995

Term of patent 14 years

(Cl. D34—5)

To all whom it may concern:

Be it known that I, William S. Brodes, a citizen of the United States, residing in New Haven, county of New Haven, and State of Connecticut, have invented a new, original, and ornamental Design for a Game Apparatus for the Spelling of Words, of which the following is a specification, reference being had to the accompanying drawing, forming part thereof, in which:

Fig. 1 is a top plan view of a game apparatus for the spelling of words embodying my new design;

Fig. 2 is a front elevational view thereof; and

Fig. 3 is an end elevational view thereof.

I claim:

The ornamental design for a game apparatus for the spelling of words, substantially as shown.

WILLIAM S. BRODES.
